MOUNTING FOR GAUGE

Leo Price, Cleveland, Ohio

Application May 20, 1955, Serial No. 36,135

Term of patent 14 years

(Cl. D52—1)

Fig. 3

Fig. 4

Figure 1 is a top plan view of a mounting for gauge, showing my new design;

Figure 2 is a side elevational view;

Figure 3 is an end view looking in the direction of the arrows 3-3 of Figure 1; and

Figure 4 is an end view looking in the direction of the arrows 4-4 of Figure 1.

I claim:

The ornamental design for a mounting for gauge, substantially as shown.
